Primary Examiner — Catherine Ho(74) *Attorney, Agent, or Firm* — Wolf, Greenfield & Sacks, P.C.(57) **CLAIM**

The ornamental design for a sign, as shown and described.

DESCRIPTION

FIG. 1 is a perspective view of a sign showing the design;
 FIG. 2 is a front view thereof;
 FIG. 3 is a rear view thereof;
 FIG. 4 is a right side view thereof;
 FIG. 5 is a left side view thereof;
 FIG. 6 is a top view thereof; and,
 FIG. 7 is a bottom view thereof.

The broken lines show portions of the article that form no part of the claimed design.

The article is shown with a symbolic break in its length. The appearance of any portion of the article between the wavy break lines forms no part of the claimed design.

1 Claim, 5 Drawing Sheets(56)
